UNITED STATES PATENT OFFICE.

WILLIAM A. KENNEDY AND ALBERT J. LOEPSINGER, OF PROVIDENCE, RHODE ISLAND, ASSIGNEES TO GENERAL FIRE EXTINGUISHER COMPANY, OF NEW YORK, N. Y., A CORPORATION OF NEW YORK.

SPRINKLER HEAD.

Application filed March 11, 1916. Serial No. 221,651.

To all whom it may concern:

Be it known that we, WILLIAM A. KENNEDY and ALBERT J. LOEPSINGER, both of Providence, in the county of Providence and State of Rhode Island, have invented certain new and useful Improvements in Sprinkler Heads; and we do hereby declare the following specification, taken in connection with the accompanying drawings, forming a part 10 of the same, to be a full, clear, and exact description thereof.

The invention relates to improvements in sprinkler-heads and is designed primarily for use in connection with that class of 15 sprinkler-heads known in the art as open sprinklers which are designed and adapted for use upon the exterior of buildings to direct a stream of water against the exterior wall of the building and through or against 20 the windows thereof.

In sprinkler-heads of this character as heretofore produced, a deflector has been employed which has a flat surface or other surface adapted to break the jet into spatters 25 arranged opposite the outlet opening and at right angles to the axis thereof. The great objection to the use of a deflector of this character resides in the fact that the stream of water issuing from the outlet opening 30 is not only broken up after it issues from the nozzle and when it strikes the surface of the deflector which is arranged at right angles to the axis of the outlet opening, but the velocity and energy of said stream is at 35 the same time greatly reduced, which in turn reduces the area of distribution.

The principal object of the present invention is to overcome the above objections and to provide a sprinkler-head of this type with 40 a deflector of such a character as not to decrease the velocity of the stream of water to as great an extent as would a flat deflector and also produce a wider and better distribution of said stream against the wall of 45 the building protected.

A further object of the invention consists in providing the sprinkler with a deflector of the above character which is arranged and adapted to receive and direct the stream 50 of water tangentially to the inner surface of said deflector.

To these ends the invention consists in the novel construction and arrangement of parts hereinafter described and particularly set

forth in the claim. In describing the invention in detail reference will be had to the accompanying drawings in which,

Fig. 1 is a side elevation of a sprinkler-head embodying our novel construction.

Fig. 2 is a vertical sectional view thereof.

Referring to the drawings, 1 represents the frame work of the sprinkler-head which comprises a tubular nozzle 2, having external threads 3 for attachment to a water supply system and the usual outlet opening 4. Secured to, or formed integral with, the frame work 1 opposite the outlet opening 4 is a deflector 5 which is preferably circular in shape and is provided with an inner curved surface 6 terminating in a pointed 70 projection 7 in line with the axis of the nozzle 3.

With the above construction it will be seen that the stream of water flowing from the outlet opening will be divided at its center by the pointed projection 7 and directed tangentially along the curved inner surface 6, thereby effecting such a gradual change in the direction of the flow of the water as not to materially reduce the velocity thereof, 75 thereby resulting in a wider distribution of the stream. Figs. 1 and 2 disclose a deflector having a curved inner surface 6' of the deflector 5 of such a curvature as to cause the flow of water passing thereover to be turned 80 back so that the direction of distribution from the deflector 5 will be at less than a right angle to the axis of the sprinkler nozzle.

It will also be seen that with our novel 90 construction of deflector, the stream flowing from the outlet opening is received by the deflector tangentially and that said stream is likewise delivered from said deflector tangentially to the plane of distribution and 95 that as a result a minimum of interference in the velocity, energy, or range of distribution of said stream results.

It will be understood that we do not wish to limit ourselves to the exact construction 100 and arrangement of parts shown as it is obvious that various changes in details may be made without departing from the spirit and scope of the invention as set forth in the claim.

What we claim as our invention and desire to secure by Letters Patent is:

A sprinkler head adapted for fire protec-

tion of a building to throw water in thin distributive stream, comprising the combination, with a nozzle, of a deflector adapted to convert the form while conserving the velocity of the jet from the nozzle; said deflector having an initial central pointed portion presented toward the nozzle and in axial alignment therewith, and curving outward from its innermost point and so making the jet tubular; a terminal smooth flaring portion, directed backward, with respect to the direction of flow through the nozzle, of such great perimeter that the said tubular stream covers it but thinly; and a smooth curved intermediate portion continuous in curvature with both said central curved surface

and said terminal flaring portion in which intermediate portion the curvature of stream direction away from the nozzle direction, and the spread in breadth of a stream 20 from its dimension at the nozzle, are sufficiently gradual to avoid breaking the stream on the surface of the deflector; the part of said terminal flaring portion which is adjacent to the said intermediate portion being 25 curved in continuity with the curvature of the intermediate portion.

WILLIAM C. KENNEDY.
